CLAIM

The ornamental design for an autonomous vehicle exterior, as shown and described.

DESCRIPTION

The present application is related to copending application Ser. No. 29/491,723, entitled Autonomous Vehicle Door, to application Ser. No. 29/491,717, entitled Tire Rim, to application Ser. No. 29/491,734, entitled Autonomous Vehicle Headlamp, to application Ser. No. 29/491,730, entitled Autonomous Vehicle Taillamp, to application Ser. No. 29/491,726, entitled Autonomous Vehicle Wing Assembly, and to application Ser. No. 29/491,727, entitled Autonomous Vehicle Rear Vent/Reflector, each of which is filed concurrently herewith, the entire disclosures of which are incorporated by reference herein.

FIG. 1 is a front perspective view of an autonomous vehicle exterior according to a first embodiment of our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown illustrate portions of the autonomous vehicle exterior that form no part of the claimed design.
